CLAIM

I claim the ornamental design for an access panel with slider handle, as shown and described.

DESCRIPTION

FIG. 1 is a front and bottom perspective view of the access panel with slider handle showing my new design.

FIG. 2 is a left side perspective view thereof;

FIG. 3 is a front view.

FIG. 4 is a front and top perspective view thereof.

FIG. 5 is right side perspective view.

FIG. 6 is rear and bottom perspective view.

FIG. 7 is a rear and right-side perspective view thereof; and,
FIG. 8 is a rear and top perspective view.
